UNITED STATES PATENT OFFICE.

JOHN J. FORSTER, OF AVALON, PENNSYLVANIA.

SOAP-PRESS.

No. 806,967.

Specification of Letters Patent.

Patented Dec. 12, 1905.

Application filed December 30, 1904. Serial No. 239,015.

To all whom it may concern:

Be it known that I, JOHN J. FORSTER, a citizen of the United States, residing at Avalon, in the county of Allegheny and State of Pennsylvania, have invented or discovered certain new and useful Improvements in Soap-Presses, of which improvements the following is a specification.

The invention described herein relates to 10 certain improvements in soap-presses, and has for its object, among other things, the provision of suitable dislodging devices whereby a pressed cake can be discharged from the pressing-mold and also the provision of suitable means for regulating the feed 15 of the blanks to the mold.

The invention is hereinafter more fully described and claimed.

In the accompanying drawings, forming a 20 part of this specification, Figure 1 is a top plan view of my improved soap-press, and Fig. 2 is a side elevation of the same. Fig. 3 is a sectional view on a plane coinciding with the axes of the plungers, and Fig. 4 is a 25 sectional view on a plane indicated by the line IV IV, Fig. 2.

In the practice of my invention a cross-head 1 is mounted in suitable bearings 2 on the frame of the machine, said cross-head 30 being provided with a bearing-block 3 for the plunger 4. This plunger is provided with a stem 5, adjustably secured to the plunger and extending back into a pocket or abutment 6 on the cross-head 1. Within this 35 pocket is arranged a spring 7, bearing at its outer end against a shoulder or collar 8, preferably made adjustable along the stem. This gives a cushioning effect to the plunger when in operation. To the front end of the 40 plunger is detachably secured a shaping-head 9, having a suitable shaping-matrix formed on its front or operative end. A similar head 10 is secured to a plunger 11, adapted to move back and forth through the 45 mold-box 12. The cross-head 1 is connected by a link 13 to a crank-pin on the power-shaft 14. On the power-shaft is secured a disk 15, having a cam-groove in its inner face for the reception of a roller 16 on the head 17. This head is connected by a rod 18 to a slide 19, provided with an arm 20, extending at right angles to the direction of motion of the slide and connected to the plunger 11.

50 The cam-groove in the disk 15 is so shaped that the head 10 will have a movement back

and forth into and out of the mold-box 12. These movements of the head 10 correspond with the back-and-forth movements of the head 9, but are differently timed—that is to 60 say, the head 10 will move into the mold-box, and after a blank has been fed, as hereinafter described, the head 9 will be moved forward, so as to compress the blank and cause it to conform to the matrices in the adjacent or 65 opposing faces of the heads 9 and 10. After the compression of the blank both heads are moved outwardly, carrying with them the compressed cake, and after they emerge from the mold-box the head 10 is drawn back to the 70 left, so as to separate from the head 9 and leave the cake free to drop.

It frequently happens that the finished cake will adhere to one or the other of the heads 9 or 10 after said heads are separated, 75 and hence provision must be made for the dislodgment of the cake, and this without any injury or deformation thereof. To this end a portion of each of the matrices is formed by blocks 21 and 22, secured to the 80 ends of stems 23 and 24, extending through the plungers 4 and 11. A lever 25, which is pivotally mounted on the plunger 11, has one end in engagement with the stem 24, and the lever is normally held by a spring 26, so as to 85 draw the block 22 into its seat or recess in the head 10. As the plunger 11 is moved forward, so as to shift the head 10 out of the mold, the lever 25 will as the head 10 reaches the limit of its outward movement strike 90 against a stationary part of the machine and force the block 22 out with a quick motion. This movement of the block 22 will free the cake from other portions of the matrix, and the shock due to such outward movement 95 will ordinarily be sufficient to separate the cake from the block 22. This block is made quite small, so that its surface in contact with the cake will be small and the adherence between the cake and block be so slight that 100 the cake will drop off, even if not dislodged by the shock or jar. A lever 27 is pivotally connected to the plunger 5 and has one end in engagement with the stem 23. The opposite end of this lever is acted on by a lever 28, 105 pivotally mounted on the frame of the machine. On the cross-head 1 is provided an arm 29, normally held by a spring 30 at an angle to the line of movement of the cross-head. As the cross-head moves to the right 110 in Fig. 1 this arm 29 will strike against an abutment or shoulder of the lever 28 and so

shift the lever that it will impart a movement to the lever 27, and thereby force out the block 21, forming a part of the matrix in the head 9. As both heads are provided with these dislodging-blocks, all liability of adherence of the cake to either of the heads is avoided.

As at times it may be desirable to grip the cake as the plungers are being separated therefrom, suitable grippers 51 and 52 are mounted on the frame of the machine. The gripper 51 is adapted to be reciprocated back and forth into and out of contact with the soap by means of lever 28, while the gripper 52 is adjusted so that its bearing-surface will almost contact with the surface of the soap as it is being drawn out of the soap-box.

A slideway or chute is arranged at the front end of the machine, preferably having a slight inclination toward the machine, and terminates at a point just above the front end of the mold-box 12. It is preferred that the bottom of this chute be formed by a belt 31, passing around a guide-pulley 32, and a pulley on the shaft 33. This shaft is preferably given a step-by-step movement by the slide 19, which is connected by a rod 48 to a lever 49, loosely mounted on the shaft 33 and provided with a pawl engaging a toothed wheel on said shaft. The blocks are retained on the belt by adjustable side pieces 34. The movement of the blocks from the chute to position in front of the mold-box is controlled by an arm 35, pivotally connected to standards 36 on the frame of the machine. At its forward end this arm is provided with a finger 37, which projects down and preferably has a hook or shoulder at its lower end. When in normal or raised position, as shown in Fig. 2, this arm, with its shoulder, will prevent the passage of the cake out of the chute. As the cross-head moves back a roller 38, carried by a standard 39 on the cross-head and normally supporting arm 35, will move back, permitting the arm 35 to drop, and thereby so shift the finger 37 as to allow a blank to drop down into a table 40 in line with the lower wall of the mold-box. As the arm moves down, carrying with it a blank, a vertical projection 41 on the arm is also moved down, so as to prevent a movement of the other blanks along the chute. As the cross-head moves to the left the arm 35 will be raised, shifting the finger 41 from in front of the blanks and bringing the finger 37 into position to receive another blank.

In order to apply a lubricant, as water, to the soap blanks as they move along the chute, a receptacle 42 is arranged on suitable standards above the chute and is provided with a regulating or valved discharge 43 to direct the water upon a flexible absorbent material, as felt, 44. This absorbent material or wiper is carried by a pivot-arm 45. In order to prevent the arm dropping down to

such position as would interfere with the passage of blanks along the chute, a supporting-finger 46 is adjustably secured to one of the supporting-standards of the receptacle and projects under the arm 45. It is preferred to make the blanks of such shape as cylindrical, so that they may be rotated in order that the lubricating fluid may be applied all around the blank. To insure this application of the lubricating material, the felt or other absorbent material is caused to bear sufficiently that the belt 31 will rotate the blank, and the absorbent material should extend a distance along the chute equal to the perimeter of the blank.

I claim herein as my invention—

1. In a soap-press the combination of reciprocating plungers, heads provided with shaping-matrices carried by the plungers, dislodging-blocks having faces forming parts of the shaping-matrices, stems connected to said blocks and extending through the plungers and means actuated by the plungers in their outward movement for shifting said stems and blocks, substantially as set forth. 85

2. In a soap-press the combination of reciprocating plungers, heads provided with shaping-matrices carried by the plungers, a dislodging-block having a face forming a part of one of the shaping-matrices, a stem connected to said block and extending through the plunger carrying the head of which the block forms a part, and means actuated by the plungers in their outward movement for shifting the stem and block, substantially as set forth. 95

3. In a soap-press, the combination of reciprocating plungers, heads provided with shaping-matrices carried by the plungers, a dislodging-block having a face forming a part of one of the shaping-matrices, a stem connected to said block and extending through the plunger carrying the head of which the block forms a part, a lever pivotally mounted on the plunger for shifting the block and means for shifting the lever, substantially as set forth. 105

4. In a soap-press the combination of reciprocating plungers, heads provided with shaping-matrices carried by the plungers, a dislodging-block having a face forming a part of one of said matrices, a stem connected to said block and extending along the plunger carrying the head of which the block forms a part, a lever pivotally mounted on the plunger and engaging the stem and means operated by the plunger in its movement to shift the lever, substantially as set forth. 115

5. In a soap-press, the combination of a feed-chute, a swinging arm provided with means for supporting a blank, a stop-finger carried by the arm and means for raising and lowering the arm, substantially as set forth. 125

6. In a soap-press, the combination of a 130

feed-chute, an arm movable in front of the chute, a blank-supporting finger and a stop-finger carried by the arm, a reciprocating cross-head provided with means for shifting the arm, substantially as set forth.

7. In a soap-press, the combination of a mold-box, a feed-chute having its discharge end arranged in line with the open end of the mold-box, an arm movable from the chute to the mold-box, a blank-supporting finger and a stop-finger carried by the arm, a reciprocating cross-head provided with means for shifting the arm, substantially as set forth.

8. In a soap-press the combination of a feed-chute means for applying lubricating material to blanks, and means for rotating the blank whereby the lubricating material may be applied all around the blank, substantially as set forth.

9. In a soap-press, the combination of a chute, a belt forming a portion of the chute and an absorbent material arranged to coöperate with the belt to change the positions of the blanks, substantially as set forth.

10. In a soap-press, the combination of a chute having a movable portion, means for shifting the movable portion and means for applying lubricating material to the blank and arranged to coöperate with the movable portion to turn the blank during the application of the lubricating material, substantially as set forth.

In testimony whereof I have hereunto set my hand.

JOHN J. FORSTER.
